BUBBLE TRAY CONSTRUCTION

George W. Watts, Whiting, Ind., assignor to
Standard Oil Company, Chicago, Ill., a corpo-
ration of Indiana

Application June 29, 1933, Serial No. 678,244

3 Claims. (Cl. 261—114)

This application relates to an improvement in bubble towers and more particularly to certain structural features and arrangement of parts having to do with the transposition of the fluid 5 from one tray level to another.

It has become substantially uniform practice to construct bubble towers of a vertical series of bubble trays and to provide downcomers for conducting the fluid from one tray level to the next 10 lower level. One of the difficulties encountered in bubble towers of this type is the condensation of the vapors in the downcomers between the tray levels brought about by the introduction of the vapors into the downcomer through the formation of a vortex in the fluid stream at the 15 head of the downcomer.

Another disadvantage attributable to the present fluid conduction arrangement of the bubble tower is the partial choking of the outlet or lower 20 end of the downcomer by the accumulation of tarry or immobile constituents of the processing fluids upon the adjacent portions of the tray wherein a pool of the fluid is maintained to seal the downcomer outlet. At times as during the 25 shut down of the tower the accumulation and further congealing of this heavy substance may completely choke the downcomer outlet opening, thus necessitating disassembly of the units and manual removal of the obstruction with conse- 30 quent waste of time and operating expense.

My invention has for an object the provision of simple means for preventing the formation of a vortex at the mouth of the downcomer by the elimination of the presence of vapor at the inlet 35 of the downcomer so that premature fractionation may not take place due to the condensation of the vapors within the downcomer and the subsequent delivery of the fluid upon a tray of lower level than that tray from which the proper and 40 required fraction is removed. In other words, I have provided a safeguard as against the withdrawal, for example of a gasoline fraction with the kerosene or next lower fraction.

Another object is to provide bubble tray fluid 45 approach which serves to discourage the accumulation of heavy and relatively immobile substance at a point where the choking of the downcomer may result, thereby eliminating the hazards of blocking the tower.

50 Other objects, the advantages, and uses of the invention, will become apparent after reading the following specification and claims and after consideration of the drawing forming a part of the specification wherein:

55 Fig. 1 is a horizontal sectional view through a

bubble tower incorporating features of the invention, baffle plates over the downcomers and bubble caps over the vapor risers being omitted from the drawing for the sake of clearness.

Fig. 2 is a sectional view substantially along the 5 line II—II of Fig. 1, and

Fig. 3 is a schematic view illustrating the manner in which premature fractionation may occur in a conventional bubble tower.

With reference to drawing, 1 represents the 10 cylindrical walls of the bubble tower and 2 a plurality of bubble tray assemblies at spaced distances from one another along the vertical axis of the tower, each establishing its own fluid level. The tray assemblies include cast trays 3 having a 15 plurality of vertically extending and rectangular wall sections 4 providing vapor chambers each of which is provided with a bubble cap 5 having depending walls which extend below the fluid level of the tray. The type of bubble tray illustrated is one wherein the fluid is caused to pass horizontally from one side of the tray to the other through parallel channels 6 formed by the vertical wall sections 4. Dams 7 and 8 which may be formed integrally with the tray serve to 20 establish a normal fluid level for the tray. The dams 7 and 8 occupy the positions of the cords of a circle and lie in planes perpendicular to the 25 axes of the fluid channels 6.

In the present embodiment I have illustrated a 30 pair of downcomers 9 for each tray assembly, substantially elliptical in cross section, although downcomers of other contour may be used with equal effectiveness, which extend downwardly 35 through a horizontal portion 11 of the tray beyond the dam 7. The upper end or inlet 12 of the downcomers may be above the level of the portion 11 but located beneath the upper level of the dam 7. Fluid passing over the dam 7 from the trays may therefore flow downwardly through the 40 downcomers 9 to the next lower tray.

A horizontal baffle 13 having a depending skirt is provided for each of the downcomers 9 and is of a size and shape to overhang the outlets 12 of the downcomers and to lie beneath the normal 45 level of fluid on the tray but sufficiently above the inlet as to permit of the uninterrupted flow of fluid therethrough. The baffles 13 may be supported upon rods 14 fixed to horizontal channels 15 as shown in Fig. 2.

I have thus effectively guarded against premature fractionation by the elimination of the possibility of the condensation and absorption of the vapor fractions by fluid in the downcomers. With reference to Fig. 3, it will be apparent that if the 50 55

vapors were permitted to pass through the downcomer indicated at A associated with the tray B from which fluid representing the lighter ends is removed by withdrawal through the pipe C that 5 the fluid withdrawn from a lower level as through pipe D representing a heavier fraction will carry with it some of the lighter ends or fractions that should have been carried off through the pipe C at the level of the tray B. Assuming that C represents a gasoline fraction whereas D represents a fraction of the nature of kerosene, the recovery 10 at C will have been deficient while the recovery at D will represent a lighter than normal fraction. The baffles 13 serve to effectively prevent entrance 15 of the vapors into the downcomer from the adjacent tray level and therefore prevent the occurrence of premature fractionation. Furthermore, the baffle, by virtue of its function in excluding vapor from the downcomer, serves to assume a 20 maximum fluid head in the downcomer, thus to promote the efficient transfer of fluid from one level to the next lower level, a feature which is of particular importance when the bubble tower is operated at or near maximum capacity.

25 With reference particularly to Fig. 2, it will be noted that the wall portion 18 of the bubble tray is concave in form, thus to provide a basin within which a pool of fluid is maintained, thereby to seal the outlet of the downcomers against the passage 30 of vapors upwardly therethrough from a lower to a higher tray level. It has been the practice in the past to maintain this pool by the provision of a wall coextensive with the tray assembly that is substantially flat and is usually located 35 in a horizontal plane, a dam being employed to maintain a level sufficiently high to insure the immersion of the lower end of the downcomers in the fluid. In my improved bubble tray construction I form the concave wall portion 18 contiguous 40 with the weir of the dam so that the portion of the greatest depth of the pool may lie between the dam and the adjacent edge of the downcomer outlets, the wall being curved gradually from that point to the adjacent tower wall 1. 45 This structure and arrangement of parts permits of the sweeping of the wall 18 by the fluid as it is discharged through the downcomer to carry heavy matter which might otherwise accumulate to choke the downcomer outlet over the dam 8 50 and through across the trays. If the heavier substances are thus maintained in circulation in the fluid system there is little possibility of harmful accumulation. Furthermore, by virtue of the curvature of the wall 18 as described the settling 55 and accumulation of tarry and other heavy substances, if such does occur, will take place at a point to one side of the outlet of the downcomers,

thus obviating the possibility of choke fluid flow and permitting of the subsequent sweeping of the accumulation into the fluid streams at a later time.

Since many modifications of my invention differing widely from the specific disclosure, but which nevertheless fall within the spirit of my invention may be made, I desire to be understood that my disclosure herein is illustrative only and not limitative and that I am to be limited only by the scope of the following claims.

I claim:

1. In a bubble tower, a plurality of bubble trays, means for conducting upwardly rising vapors through each tray, inlet and outlet pools on each tray, a downcomer for separately conducting liquid downwardly from the outflow pool on one tray to the inflow pool on the next lower tray without coming into direct contact with upwardly rising vapors, a dam higher than the inlet to said downcomer separating said outflow pool from the bubble section proper of each tray, for the purpose of maintaining a constant liquid level on said bubble tray and a baffle mounted above and spaced from the inlet of the downcomer and below the normal level of liquid on the tray to thereby prevent vapors near the inlet of said downcomer from passing therethrough with the liquid.

2. In a bubble tower, a plurality of bubble trays, inlet and outlet pools on each tray to provide for flow of reflux thereacross, dams separating inlet and outlet pools from the bubble section of said tray, said dams being sufficiently high to maintain a desired constant level of liquid on said bubble section, a downcomer for conducting liquid from the outlet pool of each tray to the inlet pool of the next lower tray, the lower end of said downcomer extending below the level of the dam separating the said inlet pool, thereby preventing access of vapors to the lower end of said downcomer, a horizontal imperforate baffle plate mounted above and spaced from the inlet of said downcomer and below the level of the dam separating said outlet pool from said bubble section, whereby vapors are prevented access to the upper end of said downcomer and flooding of the tray is prevented when the amount of reflux liquid becomes excessive.

3. The bubble tower construction of claim 2 wherein the contour of the bottom of said inlet pool is curved concavely and continuously to the top of said dam to facilitate the discharge of solid material over said inlet dam and thus prevent restriction of the flow of reflux through said downcomer by said solid material.

GEORGE W. WATTS.
